UNITED STATES PATENT OFFICE.

HARRY S. MARTIN, OF RIDGEWOOD, NEW JERSEY, ASSIGNOR TO AMERICAN ARCH COMPANY, A CORPORATION OF DELAWARE.

TUBE-ENGAGING BRICK.

Application filed August 26, 1921. Serial No. 495,586.

To all whom it may concern:

Be it known that I, HARRY S. MARTIN, a citizen of the United States, residing at Ridgewood, in the county of Bergen and State of New Jersey, have invented certain new and useful Improvements in Tube-Engaging Bricks, of which the following is a specification.

My invention relates to tube engaging brick for the construction of baffles, arches, and the like in steam boilers,—especially sectional fire arches in locomotive boilers. I aim to secure extended contact or bearing of the brick on tubes of different sizes, so as 10 to make the brick equally secure on tubes of different sizes.

Sectional fire arches of locomotive boilers are commonly constructed of a plurality of rows of fire bricks supported on water circulation tubes that extend fore and aft in the locomotive fire box. In these arches, the middle rows of bricks span the spaces between adjacent circulation tubes while the outside rows of bricks commonly extend 20 upwardly from the outside tubes to the adjacent sides of the fire box at a considerable inclination. These inclined outside or "wing" bricks are especially liable to be jarred loose and drop into the fire beneath, 25 so that it is important for them to have an extended bearing and good friction on the water tubes that support their lower ends. Accordingly, I have herein illustrated and described an embodiment of my invention with special reference to its application to such wing bricks.

Hitherto, wing bricks for sectional fire arches have been made with concave lower edges curved to fit properly on circulation 30 tubes of the size with which the bricks were specially intended to be used. Such bricks would not, therefore, fit properly on tubes of any other size; for if the tubes were smaller than the size for which the bricks 35 were designed, the bricks would make a single line contact with them at a point of tangency, while if the tubes were larger, the bricks would make a double line contact, at the outer corners of their concaved edges.

40 I obviate this difficulty by giving to the tube engaging surface of the fire brick a conformation which adapts the brick to fit snugly against tubes of different sizes, with better contact and greater area of friction 45 than in either of the cases above referred to.

In the drawings, Fig. 1 is a fragmentary diagrammatic cross sectional view through a locomotive fire box, looking aft, showing a portion of a fire arch with wing bricks that represent the best embodiment of my 60 invention at present known to me.

Fig. 2 is a fragmentary diagrammatic cross section of the tube engaging end of a wing brick such as shown in Fig. 1.

Figs. 3 and 4 are similar fragmentary 65 views, on a smaller scale than Fig. 2, illustrating the behavior of the brick with tubes of different sizes.

The sectional locomotive fire arch shown in Fig. 1 is of ordinary general construction, comprising two middle sections composed of bricks 10, 10 spanned between the fore and aft circulation tubes 11, 11 in the fire box. Inclined wing bricks 12 lean against the side sheets 13 of the fire box 70 at their arc-shaped upper ends, while their lower ends engage and fit snugly against the outer circulation tubes 11.

The tube-engaging lower end or surface 15 of each of the bricks 12 is shown in Fig. 80 2 as hollowed or concaved to engage the tubes 11. In order to make them fit snugly on tubes of different sizes, the surfaces 15 are not simply circularly concaved to a uniform radius, but are made of variant curvature, so that for each size of tube on which they are intended to be used there will be an appreciable arc of substantially identical radius and curvature. As shown in Fig. 2, the lower portion A of the brick surface 15 85 is curved to one uniform radius R, while the upper portion a is curved to a smaller uniform radius r, so that these portions are adapted to fit snugly on tubes of different sizes. The centers C and c of these portions 90 A and a are preferably so located that the upper part or corner 16 of the upper portion a lies on an extension of the arc A (see Fig. 2).

Referring, now, to Figs. 3 and 4, it will 100 be seen that when the brick 12 is used on tubes 11^a of a smaller size, the more sharply curved portion a fits the tube and makes contact with it at a multitude of points or a surface contact. When, on the other hand, 105 the brick 12 is used on tubes 11^a of a suitably larger size, the portion 15 engages and makes contact with the tube at its upper and lower extremities, as well as at a multitude of intermediate points in its lower por- 110

tion A. In either case, therefore, the surface 15 makes contact with the tube at more than two points; and on tubes of larger size, the extremity or corner 16 engages the tube 5 and assists in bringing the brick to bear properly against said lower portion. Obviously, upper portion α that engages on tubes of smaller size falls within the limits of engagement of the brick on tubes of larger 10 size.

In practice, the radii of the edge portions A and α will usually be made those of the outer surfaces of the most used tube sizes,— when, that is, the variably curved surface 15 15 is simply made up of two circular arcs, as shown.

The usual brick with tube engaging surface curved to a single radius so as to fit snugly on one size of tube 11^a would make 20 double line contact only with a larger tube 11^a and so would have relatively little friction and "holding power" on the tube. With a tube of a size smaller than those shown the brick would obviously make single line 25 contact only.

What I claim is:

1. A brick for sectional fire arch construction and the like with a hollowed tube-engaging surface adapted to make contact 30 along more than two lines with tubes of one size, and including within the limits of such

contact a portion adapted to make contact along more than two lines on tubes of smaller size.

2. A brick for sectional fire arch construction and the like having a concave tube-engaging surface of variant curvature adapted to fit snugly against tubes of various sizes.

3. A brick for sectional fire arch construction and the like having a concave tube-engaging surface including portions curved to different radii and thus adapted to fit snugly against tubes of various sizes.

4. A brick for sectional fire arch construction and the like having a concave tube-engaging surface comprising one portion curved to fit snugly against tubes of larger size and a second portion curved to fit snugly against tubes of smaller size, the outer end edge of said second portion being so located as to engage tubes of such larger size and assist in bringing the first portion of the brick to bear properly thereagainst.

5. A brick for sectional fire arch construction and the like with concave tube engaging surface formed on arcs of different radius and struck from different centers.

In testimony whereof, I have hereunto signed my name.

HARRY S. MARTIN.
